UNITED STATES PATENT OFFICE.

HARLAN S. JILLSON, OF TURNERS FALLS, AND WILLIAM H. SWEENEY, OF GREENFIELD, MASSACHUSETTS; SAID JILLSON ASSIGNOR OF HIS RIGHT TO WILLIAM H. SWEENEY, OF GREENFIELD, MASSACHUSETTS.

JACK.

1,326,451.

Specification of Letters Patent.

Patented Dec. 30, 1919.

Application filed April 17, 1919. Serial No. 290,788.

To all whom it may concern:

- Be it known that we, HARLAN S. JILLSON and WILLIAM H. SWEENEY, citizens of the United States, residing at Turners Falls and 5 Greenfield, respectively, in the county of Franklin and State of Massachusetts, have invented certain new and useful Improvements in Jacks, of which the following is a specification.
- 10 The present invention relates to improvements in jacks, adapted for use in connection with automobiles or the like, while not necessarily restricted to this use.
- An important object of the invention is 15 to provide a jack of the above mentioned character, which may be placed beneath an automobile or the like, and operated by a relatively long handle extending outwardly of the automobile.
- 20 A further object of the invention is to provide a jack of the above mentioned character which is strong, durable, and quick in action.

Other objects and advantages of the invention will be apparent during the course 25 of the following description.

In the accompanying drawings forming a part of this specification, and in which like numerals are employed to designate like 30 parts throughout the same,

Figure 1 is a side elevation of a jack embodying the invention,

Fig. 2 is a horizontal sectional view, taken on line 2—2 of Fig. 1,

35 Fig. 3 is a side elevation of the jack showing its lift head elevated,

Fig. 4 is a detail section taken on line 4—4 of Fig. 1,

40 Fig. 5 is a similar view taken on line 5—5 of Fig. 1,

Fig. 6 is a detail section taken on line 6—6 of Fig. 1,

Fig. 7 is a similar view taken on line 7—7 of Fig. 1,

45 Fig. 8 is a longitudinal section taken on line 8—8 of Fig. 1, and,

Fig. 9 is a perspective view of the operating handle.

In the drawings, wherein for the purpose 50 of illustration is shown a preferred embodiment of the invention, the numeral 10 designates a tubular standard formed upon a base 11, as shown. Slidably engaging within the tubular standard is a vertically adjustable

bar 12, having a transverse opening formed 55 therein to receive a lock pin 13, projecting radially upon the opposite sides thereof. This lock pin is adapted to be operated in diametrically oppositely arranged vertical slots 14, having shoulders or notches 15. It 60 is thus seen that the lift bar 12 may be elevated with respect to the standard 10, and by slightly turning the same the ends of the lock pin 13 may enter the notches 15, whereby the lift bar is retained elevated. This 65 construction is provided for quick adjustment.

Rigidly connected with the upper end of the lift bar 12 and preferably formed integral therewith is a cylindrical horizontal 70 sleeve 16, slidably receiving a lower horizontal shaft or rod 17. At its outer end, this rod 17, as more clearly shown in Fig. 5, is provided with a head or casting 18.

The numeral 20 designates an upper horizontal operating screw, or shaft provided 75 with screw-threads 20', which preferably extend from the left hand thereof to a point near and spaced from its center. An upper horizontal sleeve 21 slidably receives the 80 screw-threaded portion of the screw or shaft 20 but has no screw-threaded engagement therewith. The free end of the screw-threaded portion 20' of the operating shaft carries an operating and adjusting nut 22, 85 having screw-threaded engagement therewith. Means are provided to lock the nut to the sleeve 22 against rotation with relation thereto, such means comprising a set of teeth 23, formed upon the same, to engage 90 with a coacting set of teeth carried by the sleeve 21.

When the sleeve 21 is moved longitudinally of the shaft 20, away from the nut 22, the nut may be freely rotated, as is obvious.

The sleeve 21 is provided with an upwardly projecting lift head or element 23', carrying a vise jaw 24, as shown. A coacting upper sleeve 25 is rotatable upon a 100 smooth portion 26 of the upper shaft 20. The sleeve 25 is equipped with an annular flange 27, preferably formed integral therewith, and this flange is arranged near an annular flange 28, preferably formed integral with the shaft 20. Balls 29 are arranged between the flanges 27 and 28 and coact therewith to form a thrust bearing, as

shown. The sleeve 25 is provided with an upstanding vise jaw 30, coacting with the jaw 24, to form a vise.

The upper and lower shafts 17 and 20 are connected by a toggle joint structure, comprising pairs of inner and outer links 31 and 32, which cross each other, as shown. The links in each pair which cross each other are pivotally connected at points 10 equally distantly spaced from the ends thereof, as shown at 33. The lower ends of the inner links 31 are apertured, as shown at 34, for pivotally receiving trunnions 35, formed upon the sleeve 16, while their upper 15 ends are apertured, as shown at 36, for pivotally receiving trunnions 37, formed upon the sleeve 25. The lower ends of the outer links 32 are apertured, as shown at 38, for receiving trunnions 39, formed upon the head 18, as clearly shown in Fig. 5. The 20 upper ends of the links 32 are apertured as shown at 40, to pivotally receive trunnions 41, formed upon the sleeve 21.

The rear end of the shaft 20 is formed 25 square in cross-section, as indicated at 42, for detachably receiving thereon a socket 43, of an operating handle 44, of suitable length. This handle is preferably formed in sections 45, hinged together, as shown at 46, so 30 that the handle may be folded. The outermost section 45 is equipped with a transverse hand grip 47, also formed in pivoted sections 48 and 49, as shown.

The operation of the jack is as follows:

35 The jack is placed beneath the load with the head or element 23' in contact therewith. The operating handle 44 now has its socket 43 placed upon the extension 42 of the operating shaft 20, whereby this operating shaft 40 may be rotated. As the nut 22 engages with the sleeve 21 and is normally held against rotation, the shaft 20 will be moved longitudinally to the left, the shaft 17 also moving in the same direction. The links 31 45 and 32 are thereby turned upon their pivots 33, and are expanded, as illustrated in Fig. 3, whereby the load will be lifted.

It is obvious that a quick adjustment of the jack may be effected, before it carries the 50 load, by shifting the operating shaft to the left a suitable distance to properly expand the links 31 and 32, the nut 22 being then freely rotatable, so that it may be turned, and subsequently to this turning, its teeth 55 will engage the teeth of the sleeve 21. The shaft 20 will then be turned in the usual manner to raise the load.

It is to be understood that the form of our 60 invention herewith shown and described is to be taken as a preferred example of the same, and that various changes in the shape, size, and arrangement of parts may be resorted to without departing from the spirit of our invention or the scope of the subjoined claims.

Having thus described our invention, we claim:

1. In a jack of the character described, a standard, a sleeve connected therewith, a shaft slidable within the sleeve, an operating shaft arranged above the first named shaft and having a screw-threaded portion, a second sleeve slidably receiving the screw-threaded portion of the operating shaft and having no screw-threaded engagement therewith, a third sleeve rotatable upon the operating shaft, a nut having screw-threaded engagement with the screw-threaded portion of the shaft and having means whereby it may be held by the second named sleeve 80 against turning movement with relation thereto, a lift member carried by the second named sleeve, means to rotate the operating shaft, a pair of links pivotally connected with the first and third sleeves, and a second pair of links pivotally connected with the first pair of links and having pivotal connection with the first named shaft and the second sleeve. 85

2. In a jack of the character described, a 90 standard, a substantially horizontal sleeve connected therewith, a substantially horizontal shaft slidable within the sleeve, a substantially horizontal operating shaft arranged above the first named shaft and having a screw-threaded portion, a second sleeve slidably receiving the screw-threaded portion and having no screw-threaded engagement therewith, a third sleeve rotatably receiving the smooth portion of the operating 100 shaft, a nut having screw-threaded engagement with the screw-threaded portion of the operating shaft, means whereby the nut may be locked to the second sleeve against rotation with relation thereto, a lift element carried by the second sleeve, means to rotate the operating shaft, a pair of links pivotally connected with the first and third sleeve, and a second pair of links pivotally connected with the first pair of links and having 110 pivotal connection with the first named shaft and the second sleeve. 105

3. In a jack of the character described, an operating shaft having a screw-threaded portion, a sleeve slidably receiving the screw-threaded portion and having no screw-threaded engagement therewith, a nut engaging the screw-threaded portion of the operating shaft and having means whereby it may be locked to the sleeve against rotation 120 with relation thereto, pivoted links connected with the sleeve and one end portion of the operating shaft, means for supporting the pivoted links, means to rotate the shaft, and a lift element carried by said sleeve. 115

4. In a jack of the character described a standard, a substantially horizontal sleeve connected therewith, a substantially horizontal shaft slidable within the sleeve, a substantially horizontal operating shaft ar- 130

ranged above the first named shaft and having a screw threaded portion, a second sleeve 5
slidable receiving the screw threaded portion and having no screw threaded engagement therewith, a third sleeve rotatably receiving the smooth portion of the operating shaft, a flange formed upon said third sleeve, a flange formed upon said operating shaft, 10
complementary grooves formed in said flanges and coacting to form a ball race, balls arranged within said grooves, a nut having screw threaded engagement with the screw threaded portions of the operating shaft, means whereby the nut may be locked 15
to the second sleeve against rotation with relation thereto, a lift element carried by the second sleeve, means to rotate the operating shaft, a pair of links pivotally connected with the first and third sleeve, and a second pair of links pivotally connected 20
with the first pair of links and having pivotal connection with the first named shaft and second sleeve.

In testimony whereof we affix our signatures in presence of two witnesses.
